UNITED STATES PATENT OFFICE.

ALBERT SYDNEY ROLLINGS, OF CAMBRIDGE, MASSACHUSETTS, ASSIGNOR TO BOSTON-1915 (INC.), A CORPORATION OF MASSACHUSETTS.

DESIGN FOR A BUTTON.

40,705.

Specification for Design.

Patented May 24, 1910.

Application filed March 28, 1910. Serial No. 552,119. Term of patent 7 years.

To all whom it may concern:

Be it known that I, **ALBERT SYDNEY ROLLINGS**, a citizen of the United States, residing at Cambridge, in the county of Middlesex and State of Massachusetts, have invented a new, original, and ornamental Design for a Button, of which the following is a specification, reference being had to the accompanying drawing, forming part thereof.

Figure 1 is a plan view of a button, showing my new design. Fig. 2 is a side elevation of the button.

I claim:

The ornamental design for a button, as shown.

ALBERT SYDNEY ROLLINGS.
